UNITED STATES PATENT OFFICE.

MARTIN M. PEARLMAN, OF CLARKSBURG, WEST VIRGINIA.

APPARATUS FOR THE EXTRACTION OF ZINC.

1,167,925.

Specification of Letters Patent. Patented Jan. 11, 1916.

Application filed March 9, 1915. Serial No. 13,140.

To all whom it may concern:

Be it known that I, MARTIN M. PEARLMAN, a citizen of the United States, residing at Clarksburg, in the county of Harrison and State of West Virginia, have invented certain new and useful Improvements in Apparatus for the Extraction of Zinc, of which the following is a specification.

This invention relates to apparatus for the extraction of zinc.

In the process of distillation for the extraction of pure zinc a retort is operatively connected with a filterer and condenser. Apparatus of this character have been employed wherein the filterer has been located within the retort, which is not practical, owing to the retort being subjected to such intense heat as to render it practically, if not wholly, impossible to remove the filterer in the presence of the heat and moreover, incident to the intense heat, there is a consequent expansion and contraction of the retort with relation to the filterer, with the result that the filterer sticks to the retort to such an extent that it is a physical impossibility to get it out of the retort. Furthermore, these filterers have to be taken out once every twenty-four hours, and if, because of this frequent removal of the filterers, the latter are made of such size as to prevent them from sticking to the retort incident to contraction and expansion they will not stand up properly and perform the work for which they are intended. In other words, if the filters were made small enough so that they would not stick they would not stand up in the front of the retort but would fall down and therefore could not properly perform the work when it is considered that the retorts are subjected to a heat anywhere from 1800 to 2000 degrees. When it is considered that these retorts are subjected to such intense heat it is apparent that the filterers cannot be removed from the retorts in the presence of the heat and to turn down the fires for the purpose of permitting removal of the filterers results in the waste of time, labor and expense.

In the present instance, I combine the filtering and condensing chambers together, and am enabled to obtain satisfactory results without disposing the filtering chamber within the retort, thereby overcoming possibility of the filtering chamber sticking to the retort and enabling the attendant to re-

move said chamber from coöperative relation with the retort while the latter is being subjected to heat and without diminishing, but rather increasing the capacity of the filtering chamber.

With the above and other objects in view the invention consists in the construction and novel combination of parts hereinafter fully described, illustrated in the accompanying drawings, and pointed out in the claims appended hereto, it being understood that various changes in the form, proportion, size and minor details of construction, within the scope of the claims, may be resorted to without departing from the spirit or sacrificing any of the advantages of the invention.

In the drawing:—Figure 1 is a sectional view illustrating one embodiment of my invention. Fig. 2 is a similar view, illustrating another embodiment of my invention. Fig. 3 is a view, partly in perspective elevation and partly in section, illustrating the combined filtering and condensing chamber. Fig. 4 is a view of one form of filtering chamber partly in perspective and partly in section.

Referring now more particularly to the accompanying drawings, the reference character 10 indicates a retort of any suitable character which is mounted at its outer end in an opening 11 of the wall 12 of the furnace, and which, as usual, is disposed in any inclined plane with its inner end mounted on a shoulder 13. The retort is located over the heating means of the furnace, (not shown).

In one embodiment of the present invention I form the filtering and condensing chambers together in an integral casing, as shown in Fig. 1, and in another instance they are formed separately. Otherwise the two forms of invention are substantially the same. Describing more minutely the first embodiment of the invention, the filtering chamber 14 is separated from the condensing chamber 15 by means of an integral partition 16, provided with openings 17 which establish communication between the chambers for the passage of zinc vapors into the condensing chamber.

The walls of the filtering chamber taper or converge and the closed minor ends of the same is provided with an opening 18, through which zinc vapors issuing from the

retort pass into the filterer and through the filtering refractory or other mass *a* and subsequently to the condensing chamber.

The condensing chamber 15 has its walls 5 tapering or converging outwardly as shown, there being provided the usual clay stoppered outlet to withdraw the metal which is arrested and separated in the filtering chamber from the zinc vapors, the tapering or inclined wall of the filtering chamber facilitating flow of the metal toward said outlet.

In the second embodiment of the invention, the filtering chamber 14' is formed separately from the condensing chamber 15', 15 as stated, and the filtering chamber has its rear wall provided with an aperture 17' to establish communication between the chambers, which may be connected together in any suitable manner. In this second embodiment of the invention the filtering chamber has openings 18' to establish communication between it and the retort 10, and it also has an outlet 20 as in the first form described, although slightly different with regard to the position thereof, due to the slightly different formation of the inclosing walls of the filtering chamber in this second embodiment, as compared with the first.

In the use of my invention, the filtering chamber is not inserted into the retort, but on the other hand, it is arranged outside of the retort and in such relation thereto as to be entirely away from the fire box or the heat to which the retort is subjected. For instance, the minor end of the filtering chamber is inserted into the retort at the outer open end of the latter, and owing to the tapering wall formation of the filtering chamber, it engages the mouth or open end of the retort only at the extreme inner edge of the retort, as clearly shown in the accompanying drawings, with the result that there is little or no danger of the filtering chamber becoming stuck to the retort and in any event, enabling the attendant to remove the chamber at any time desired without the attendant being subjected to the intensity of the heat to which the retort is being subjected and without the necessity of shutting down the plant.

The filtering and condensing chambers may be readily supported in the aforesaid relation to the retort in any suitable manner. One way in which this may be accomplished 55 is to provide a suitable supporting device 21, to which may be pivotally connected an arm 22 adapted to engage the outer end of the condensing chamber, and the latter being formed with or secured firmly to the filtering chamber, it may be effectively supported with its smaller end in the outer open end of the retort.

What is claimed is:—

1. The combination with means for the extraction of zinc including a retort having

an open outer end, of a combined filter and condenser consisting of a hollow casing provided intermediate its ends with a transverse partition dividing the casing into an inner filtering chamber and an outer condensing 70 chamber, the inner end of the casing fitting within the open end of and engaging the walls of the retort to form a closure for the same.

2. The combination with means for the extraction of zinc including a retort having an open outer end, of a combined filter and condenser consisting of a hollow casing provided intermediate its ends with a transverse partition dividing the casing into an inner 80 filtering chamber and an outer condensing chamber, the inner end of the casing being tapered and fitting within the open end of the retort and engaging the walls of the retort and forming a closure for the same. 85

3. The combination with means for the extraction of zinc including a retort having an open outer end, of a combined filter and condenser consisting of an oppositely tapered casing provided at a point intermediate of 90 its ends with a transverse partition dividing the casing into an inner filtering chamber and an outer condensing chamber, the inner end of the casing fitting within the open end of the retort and engaging the walls thereof 95 and forming a closure for the retort.

4. The combination with means for the extraction of zinc including a retort having an open outer end, of a combined filter and condenser consisting of an oppositely tapered 100 casing provided at a point intermediate of its ends with a transverse partition dividing the casing into an inner filtering chamber and an outer condensing chamber, the inner end of the casing fitting within the 105 open end of the retort and engaging the walls thereof and forming a closure for the retort, and the said filtering chamber having a downwardly and outwardly inclined bottom and provided at the lower end thereof with an outlet. 110

5. The combination with means for the extraction of zinc including a retort having an open outer end, of a combined filter and condenser consisting of an oppositely tapered 115 casing provided at a point intermediate of its ends with a transverse partition dividing the casing into an inner filtering chamber and an outer condensing chamber, the inner end of the casing fitting within the 120 open end of the retort and engaging the walls thereof and forming a closure for the retort, and the said filtering chamber having a downwardly and outwardly inclined bottom and provided at the lower end thereof with an outlet, and the said partition being provided above the outlet with an aperture forming a communication between the filtering and condensing chambers. 125

6. The combination with means for the 130

extraction of zinc including a retort having an open end, of a tapered filter having its minor end fitting within the open end of the retort and engaging the walls thereof and forming a closure for same, said filter being located substantially exteriorly of the retort and containing filtering material and pro-

vided with a zinc vapor outlet and a metal outlet located outside of the retort.
